AUTOMATIC TRAFFIC CONTROL SYSTEM

Paul P. Horni, Newark, N. J.

Application September 25, 1930, Serial No. 484,334

4 Claims. (Cl. 177—337)

This invention relates to an automatic traffic control system of the type whose signals are subject to control by the traffic.

Among the traffic control systems in use heretofore, a motor driven commutator or circuit-breaker operated continuously to flash the traffic lights on and off to procure the successive signal cycles, whether or not the traffic was such as to warrant continuous control. Usually a great deal more traffic traverses one street than the other intersecting street, but with the usual continuous traffic signal the heavy traffic traversing one street must stop periodically even when there is no cross-traffic requiring such action, thereby causing unnecessary retardation of traffic, which would move more rapidly if the traffic signal did not interfere with it unnecessarily. Accordingly, a continuous traffic signal system, though warranted by a certain amount of cross-traffic at times such as during the rush hours, does more harm than good in such a case.

In many communities, in order to economize on power and save the equipment, it has become the practice to shut off the continuous traffic control equipment during the hours between midnight and early morning when traffic is very light, but because night drivers usually travel at high speed, the control of traffic becomes more necessary at night than during the day time, when the roads are not as free of traffic as to permit high speed operation of vehicles. Accordingly, since the thoroughfares are without any traffic control whatever, because of the custom of shutting the traffic lights off late at night, a dangerous traffic condition exists and many fatal accidents have occurred for this reason. Such a practice would not be necessary if the traffic system were normally inactive or dormant except at a time when converging or intersecting traffic made it necessary, whether late at night or during the day, whereby the system would itself economize on power, extend the life of the lamps, reduce servicing, and save the equipment against wearing out rapidly due to continuous use.

Also in the instance where a continuously operating traffic signal is located at an intersection where the cross-traffic is lighter than is sufficient to warrant the continuous signal, a vehicle operator, upon seeing the green light ahead while still a considerable distance from the intersection, races to cross the intersection before the signal flashes against him, which he would not do if there were no traffic signal ahead of him. This is a source of considerable danger and might be largely avoided if the traffic signal were only

employed when the cross traffic warrants it, i. e. a discretionary traffic control initiated upon command, such as by a traffic officer, is desirable.

It is accordingly the principal object of this invention to provide an automatic traffic signal control system whose operation is initiated only upon command to dispose of whatever cross-traffic there may be at any one time, and thereafter lapses into inactivity to permit the usual or heavy traffic to flow unimpeded until such time that there is cross-traffic which requires control of the intersection. This system, while fully mechanical in operation, is discretionary in function in that it only operates when traffic conditions make traffic control necessary, whereby the enumerated objections to traffic control systems employed heretofore are obviated. By means of this new system, traffic is expedited and not hindered when there is no reason for stopping it, and the thoroughfares and their intersections are subject to traffic control throughout the twenty-four hours of every day, whereby traffic is dispatched safely at all times and all of the time without excessive use of power and the equipment since the system only operates upon command when cross or convergent traffic requires its operation. In fact, very much less power is used than by the continuous cycle traffic equipment, less servicing and repair work is needed, and the life of the lamps is extended, as is the life of the equipment as a whole.

Another object of this invention is to provide an automatic traffic control system which is entirely self-contained and is provided with its own local battery, so that the system may be installed in outlying districts where outside power is not readily available. Furthermore, the system may be installed without the necessity of making arrangements with the power companies or running power lines, often from considerable distances, to the intersection where the system is installed.

Another object of this invention is to provide a system of the type described in which a complete signal cycle for controlling both the main highway and the cross street traffic is initiated by a vehicle or pedestrian approaching the intersection from the cross street, and this cycle of operations may be extended a predetermined number of times by additional impulses caused by successive vehicles or pedestrians until a predetermined time interval has elapsed, whereupon the signals are restored to dispatch the main highway traffic until another signal cycle is com-

pleted when another cross traveling vehicle or pedestrian can again initiate the signal cycle.

Another object of this invention is to provide a signal system of the type described in which a vehicle seeking to negotiate a turn from one of the streets of the intersection in a signal zone either appropriates the signals to his benefit from other vehicles which are under the control of the signals at that time or else initiates signals, if the signal system is not otherwise in operation, whereby other vehicles at the intersection are stopped until the turn has been completed by the vehicle who initiated or appropriated the signals.

A further object of this invention is to provide means along the roadside at a sufficient distance ahead of the intersection under automatic traffic control to warn approaching vehicles that they are entering an automatic signal zone and must be prepared for a change in signal, if signals are being shown, or prepared for the initiation of signals if none are shown.

These and other objects of this invention are realized in a preferred embodiment thereof, comprising a local battery which supplies current to the signal operating mechanism and the signal lights, this battery and the signal mechanism being conveniently located adjacent the intersection in any suitable way and no outside power is required for operation of the signal system. Placed in the surface of the cross street adjacent the intersection, in the sidewalk or otherwise adjacent the curb at opposite sides of the main highway at the intersection, and in some instances in the center of the main highway on the right-hand side of the same approaching the intersection, are contact means whereby the weight of an object closes an electrical circuit to initiate the operation of signal system or alter the operation thereof. The first contact means mentioned, i. e., those located in the surface of the cross street adjacent the intersection, are subject to operation by the weight of a vehicle approaching the intersection on the cross street from either direction; the second contact means, i. e., those placed on the sidewalk or adjacent the curb on opposite sides of the main highway, are adapted to be operated by the weight of a pedestrian seeking to cross the main highway whose traffic is normally unimpeded by traffic lights; and the third contact means mentioned, i. e., those placed in the middle of the main highway adjacent the intersection are adapted to be operated by a vehicle seeking to negotiate a left turn from the main highway into the cross street. Any one, any two, or all three of these arrangements may be used in conjunction with each other, and in order to illustrate preferred arrangements of the invention I have described the combination of the cross street vehicle and pedestrian control as a complete system and also a cross street vehicle, pedestrian and left turn vehicle control as another separate and complete system.

Let it be assumed that a vehicle is approaching the intersection from a cross street with due care, having been warned several hundred feet ahead of the intersection that he is approaching the zone of automatic signal control. If no other vehicle has immediately preceded the vehicle in question toward the intersection along the cross street, the main highway traffic is traveling without interruption by the traffic lights, as the traffic lights are not illuminated in this instance. As the cross traveling vehicle nearly reaches the intersection, the weight thereof closes the street

contacts and the signal cycle is initiated by a series of steps which includes the starting of an electric motor which, by a series of cam controlled contacts, performs the successive operations necessary to complete the normal signal cycle which involves flashing the red, green and amber lights in proper succession against both the main highway traffic and the cross traveling vehicle that has initiated the signal cycle. It will be apparent from this discussion that the main highway traffic is stopped until the cross traveling vehicle has crossed the main highway and proceeded on its way, after which time the signal lights are again extinguished and the normal main highway traffic proceeds in the usual uninterrupted manner.

As mentioned above, means are also provided for permitting a pedestrian to control the traffic at the intersection if he seeks to cross the main highway. Of course he can freely cross the cross street, as it is assumed that the traffic thereon is not as dense as main highway traffic. Accordingly, if a pedestrian seeks to cross the main highway, he steps upon one of the pedestrians' contacts on the sidewalk or otherwise adjacent the curb at an intersection at a position so that he can cross the main highway. The weight of the pedestrian operates this contact and the signal cycle just described in connection with the cross traffic is initiated and when the red light is flashed against the main highway traffic and the cross street green lights are lighted, the pedestrian may safely cross the street, the time interval being sufficient to permit him to do so without danger. If a second pedestrian immediately following the first one steps on any one of the four pedestrians' buttons placed at the four corners of the intersection, the signal cycle is delayed so that the cross street green light and the main highway red light remain energized for a longer period. This time can be extended by the successive operation of any one of the pedestrians' buttons by four successive pedestrians, each of which tends to slow up the signal motor a longer time until the predetermined maximum time has elapsed, whereupon the signals are restored to their initial condition.

Means may also be provided for permitting a vehicle to make a left turn from the main highway into the cross street whether or not the signal cycle is in operation, either from initiation by a cross traveling vehicle or by a pedestrian seeking to cross the main highway. It is only necessary for the vehicle which seeks to negotiate a left turn to pull up to the center of the main highway adjacent the intersection, whereupon the weight of the vehicle closes the contacts to either initiate a new signal cycle or to interrupt the normal signal cycle which may be in operation at that time. The effect of this interruption or new initiation of the signal cycle is to stop all cross traffic and main highway traffic, except that in the direction from which the left turning vehicle seeks to turn into the cross street, and a separate motor is provided whose function is to control the signals in such a way that a predetermined period of time is allowed the left turning vehicle to negotiate the turn from the main highway into the cross street. After this special signal cycle has been completed, the signals are restored to their initial position, unless intervening circumstances such as mentioned above change them. It will be seen that the left turning vehicle takes prece- 75

dence, and this is desirable in order to clear the main highway of left turning vehicles immediately, as they otherwise obstruct traffic and retard normal flow of main highway traffic.

5 Other details of the invention will become apparent in the following description of preferred embodiments thereof which constitute complete signal systems which are automatically operated by the traffic only under such circumstances 10 when the operation is required by traffic conditions as otherwise the mechanism does not operate and its length of life is increased, its consumption of power is small, and by providing a self-contained system it is admirably suited for 15 controlling traffic in outlying districts or in such portions where the main highway traffic greatly exceeds cross traffic, whereby no signals are normally required for main highway traffic except where infrequent cross traffic appears.

20 For a better understanding of the invention, reference is made to the accompanying drawings, in which

Figure 1 is a schematic electrical diagram of the automatic traffic control system of this invention;

Figs. 2 and 2a are complementary drawings which jointly illustrate schematically a representation of the traffic control system of this invention modified to include left-turning traffic control;

30 Fig. 3 is a diagram of a road or street intersection equipped with the new control system, showing the arrangement of the vehicle and the pedestrian contact;

35 Fig. 4 is a similar diagram including curb indicators for warning the operator of a vehicle that he is approaching a zone of traffic control; and

40 Fig. 5 illustrates in enlarged detail the curb warning indicators.

In the arrangement of this invention, the traffic light housing 10 is mounted in the center of the intersection of the cross street with the main highway in the usual way, as shown in Figs. 3 45 and 4. Along the curb on either side of both the cross street and main highway are placed the warning indicators 11 and 12 which are placed several hundred feet ahead of the intersection and are reflectors, lights, or are otherwise arbitrarily arranged or inscribed with warning legend to inform an approaching vehicle operator that he is approaching a zone of automatic signal control, and that he must be watchful of signals. If the signals are in operation because they were 55 initiated by a cross-traveling vehicle, the approaching vehicle can observe the lights, but the indicators 10 and 11 additionally warn him that the signal control is automatic.

The operating mechanism, other than the 60 lights 10, the warning indicators 11 and 12, and the pedestrian- and vehicle-controlled contacts, is placed in a suitable housing, and the battery which feeds the mechanism may also be placed in the same or adjacent housing, whereby both the 65 mechanism and the battery are readily accessible for inspection, repair and replacement.

Referring to the diagram of Fig. 1, it will be seen that in the surface of the cross street in the path of traffic approaching the intersection from 70 either direction are placed the vehicle controlled contacts 23 and 23'. These contacts may be simply a treadle which is depressed by the weight of the vehicle to connect the contacts electrically or it may consist of a diaphragm which, when depressed, moves a column of liquid to close a

remote switch, or to operate lever or gear systems for the same purpose, and the like, it being understood that any equivalent arrangement will serve the purpose, i. e., that of closing a switch when a vehicle comes to rest at the proper point 5 on the cross-street.

Assuming that a vehicle on the cross-street is approaching the intersection from the north. If no vehicle immediately ahead has just negotiated the intersection from the cross-street, no traffic 10 lights are visible and the main highway traffic flows uninterrupted by traffic lights or cross traffic, the object being to dispatch the main highway traffic as quickly as possible. Several hundred feet before the approaching cross-street vehicle reaches the intersection, the operator thereof is warned that he is entering a zone of automatic signal control by the warning indicators 11 and 12, shown in Figs. 4 and 5, and heeding the warning the operator slows the vehicle 15 down.

Cross-street vehicle traffic control

Referring to Fig. 1, as the cross-traveling vehicle nearly reaches the intersection the vehicle 25 closes street contact 23, and a circuit is closed which is traceable from battery 20, closed line switch 21, wire 22, contact 23, wire 24, relay 25 and return through wire 26 to battery. Relay 25 pulls down its armature 26 to close contacts 27, 30 which closes circuit from battery 20, wire 22, wire 28, contacts 27, armature 26, wire 29, separate wires 30 and 31, which energize relays 32 and 33, respectively, which are connected by wires 34 and 35, respectively, through wire 26 to battery 20. 35 Relay 32 pulls down its armature to connect contacts 37, the armature being locked in closed position by pawl 38. Similarly, relay 33 pulls down its armature 39 to connect contacts 40, and the armature 39 is locked in closed position by pawl 40 41. Both relays 32 and 33 control the same circuits, i. e., the two circuits of the motor A, the former circuit being traced from battery 20, wire 22, wire 42, contacts 37, armature 36 of relay 32, wire 43, motor A, and wires 44, 34 and 26 to battery 20, while the latter circuit is traced from battery 20, wire 22, wire 45, contacts 40, armature 39 of relay 33, selector switch segment 46, switch arm 17, switch contact 18, wire 19, the motor A, and wires 48, 44, 34 and 26 to battery 20. 50

As the motor begins to rotate, cam 50, mounted on cam shaft 51, driven by the motor A, drops its follower 52 off its high point 53 to the no motion surface which comprises the greater proportion thereof. This action causes spring contacts 54 55 to close, which initiates the signalling operation. At this time high point 59 of cam 60 has not moved its follower 58 and contacts 61 are closed. Also follower 66 lies in the notch of cam 67 and contacts 71 are closed while contacts 68 60 are open.

As seen above, wire 47 was energized by closed relay 32 when the cross street vehicle contacts 23 were closed. Therefore beginning with wire 47, a circuit may be traced through wire 55, contacts 54, follower 52, wires 56, 57 and 62, follower 58, contact 61, wire 63, and terminal 64 where the circuit divides. One branch thereof follows wire 74 red cross lights 75, wires 76, 34 and 26 back to battery 20, while the other branch 70 circuit is completed from terminal 64, wire 65, follower 66, contact 77, wire 79, amber main lights 78, wires 72, 73, 34 and 26 back to battery 20. It will be seen that the warning amber lights 78 are flashed to main highway traffic, and the 75

red stop lights 75 to cross traffic including the vehicle which initiated the signals by closing street contacts 23 (or 23').

As cam shaft 51 rotates further, follower 58

- 5 rides up on the high point 59 of cam 60 and contacts 61 are opened, thus breaking the circuit previously traced to the main amber lights 78 and cross red lights 75 and extinguishing them. Simultaneously, the follower of cam 90 drops in 10 the notch thereof, and closes contacts 86, thus closing a circuit from energized wire 47, wire 55, contacts 54, wires 56, 57 and 85, contacts 86, to terminal 106 where the circuit divides, one branch following wire 107, solenoid 108 and wires 34 and 26 back to battery 20. Energization of 15 coil 108 withdraws locking pawl 38 and releases armature 36 of relay 32 to break the circuit across contacts 37 and thru wire 41 to a motor which was energized by the closing of street contacts 20 23 (or 23') by the cross traffic. The circuit to motor is maintained, however, through the parallel circuit closed by solenoid 33 from battery 20, wires 22, 26, 45, contacts 40, closed by the armature 39 of relay 33, selector switch segment 25 46, switch arm 17, switch contact 18, wire 19, motor, wires 48, 44, 73, 34 and 26 back to battery 20, so the motor keeps on rotating.

It will be remembered that the circuit previously traced upon closure of contacts 86 by 30 cam 90 divided at terminal 106 and the remaining branch may be traced through wires 87 and 109 to main red lights 110, wires 72, 73, 34 and 26 back to battery 20. The red lights 110 accordingly stop main highway traffic. Another 35 division of this circuit may be traced from aforementioned terminal 106, wire 87, follower 81 of cam 80, closed contacts 84, wire 111, cross street green lights 112, wires 76, 34 and 26 back to battery 20. Thus cross traffic receives the "go" signal by its 40 green lights 112 and main highway traffic simultaneously receives the "stop" signal by the red light 110.

Next, the followers of cams 60 and 80 drop off the high point thereof and close contacts 61 and 83, respectively, and open contacts 84, the latter action breaking the circuit to the cross green lights 112, while the main red light remains lit. This new circuit is traced from energized wire 47, wire 55, contacts 54, wires 56, 57 and 85, 45 contacts 86, terminal 106, wire 87, contacts 83, terminal 120 where the circuit divides, wire 89, cross street amber lights 85', and wires 76, 34 and 26 to battery 20. Thus the cross street green lights 112 are extinguished and the cross street 50 amber lights 85' are simultaneously lighted.

The other branch of the circuit just traced 55 leads from terminal 120, through wire 121, coil 122 and wire 26 back to battery. Energization of coil 122 pulls pawl 124 away from ratchet 125 and causes the pawl 124 to knock pawl 169 also away from ratchet 125 to permit spring 170 to return the step-by-step switch to its initial position so that its arm 17 engages the initial contact 18. This restoring action is ineffective when 60 the step-by-step switch has not been actuated as is the case in the circumstances described, but the switch has a function which will be described later, and this is the manner in which it is restored after performing that function.

70 Now referring to the closure of contacts 61 by cam 60, this action takes place an instant after the action of cam 20 and effects the illumination of cross red lights 75 and main amber lights 78. This circuit is traceable from wires 75 47 and 55, contacts 54, wires 56, 57 and 62, con-

tacts 61 and terminal 64, where the circuit divides, one branch through contacts 77 wire 79 and amber main lights 78, while the other follows wire 74 to cross red lights 75. Next the follower of cam 90 rides upon its no-motion surface and 5 opens contacts 86. The opening of contacts 86 breaks the circuit through the main highway red lights 110 and the cross street amber lights 85, which had been initiated by contacts 83 of cam 80. Opening of contacts 86 also de-energized 10 reset coil 108 of relay 32 so that it is ready for the next setting action. Immediately after the action just described the follower 66 of cam 67 rides up on the no-motion surface of the cam to open contacts 77 and close complementary contacts 68 to extinguish main amber lights 78 and illuminate green main lights 70, while cross red lights 75 remain illuminated. Thus main highway traffic is restored and cross traffic is stopped by the red lights 75 after having passed the car which initiated the signal action by closing cross-street contacts 23 (or 23'). Fig. 1 illustrates this condition of traffic control.

Meanwhile the motor continues to rotate until follower 101 of reset cam 100 drops into the 25 notch 105 thereof to close contacts 102. The circuit thus established is traceable from battery 20, wires 22 and 45, contacts 40 of relay 33, wires 47 and 55, contacts 54, wires 56 and 104, contacts 102, and wires 103 to terminal 113, 30 where the circuit divides, one branch traversing reset coil 114, and wires 115 and 26 to battery 20, and the other branch traversing wire 117, reset coil 118, and wire 119 and 26 back to battery 20. The energization of solenoid 114 pulls 35 pawl 41 from armature 39 to release it so that the connection between contacts 40 is broken thus deenergizing the entire system and the motor stops rotating and all lights are extinguished, main highway traffic continuing without interruption as the signal system is controlled by the cross traffic. The follower 52 rides up on high point 53 of cam 50 to disconnect contacts 54. The energization of solenoid 118 has no effect under traffic conditions just described and its function 40 will be described later.

Pedestrian traffic control

Provision is also made for control of the traffic lights by pedestrians who desire to cross the 55 main highway, which, it will be remembered, is normally open to traffic at all times except when a vehicle approaching from a cross street energizes the signalling system to stop the main highway traffic and permit the cross street traffic to cross the main highway. At opposite sides of the main highway at the intersection thereof with the cross street are placed the buttons 150, these buttons being preferably in the form of treadles upon which a pedestrian steps in the 60 act of crossing the street, and are placed either on the curb, in the sidewalk adjacent the curb, or immediately below the curb. The buttons or treadles may constitute a movable contact which is depressed by the weight of the pedestrian to 65 bridge contacts 151 to close a circuit, which may be traced from battery 20, wires 22 and 152, contacts 151 and 150, wires 153 and 154, contacts 155 normally bridged by the armature 156 of relay 157, wire 158, selector switch solenoid 159, 70 and wires 160 and 26 back to battery 20.

The circuit just traced divides at terminal 161 and the other branch may be traced from terminal 161, wire 162, relay 163, and wire 26 back to battery 20. Relay 163 is the same type as relay 75

25, being connected in parallel therewith and performs the same function as the latter relay, that is, initiates the automatic signal operation in exactly the same way as was described in connection with the initiation of the signal system by closure of the cross street vehicle contacts 23 by the vehicle approaching the main highway intersection from a cross street. Accordingly, it will not be necessary to trace this same operation, it 10 being sufficient to point out that closure of relay 163 by the pedestrian's button 150 holds down its armature 164 to bridge contacts 165. This initiates a circuit traceable from battery 20, wire 22, wire 28, relay contacts 165, relay armature 164, wires 166 and 29, relay 32, and wires 34 and 26 back to battery 20. Energization of relay 32 closes relay contacts 37 to close the circuit to the motor A to start the signal system into operation in the manner previously described. The sequence of signals varies from amber to red on the main highway, and from red to amber to green on the cross street, which is the signal condition stopping the main highway traffic to permit the pedestrian to cross the main highway 25 in safety.

It will be recalled that when the pedestrian stepped on one of the buttons 150 solenoid 159 of the selector or step-by-step switch was energized, this action causing the armature 167 to be 30 pulled upwardly about its pivot 168. At the end of the armature 167 there is a spring pressed pawl 169 engaging the toothed pawl 125 carrying the switch arm 17. Upward movement of the pawl causes ratchet 125 to rotate one notch against the tension of spring 170, so that contact arm 17 moves from the first switch point 18 to the second switch point 126. As these two switch points are connected in parallel to the motor lead 19, this action has no effect on the motor A, and it keeps 40 running at the same speed.

However, should a second pedestrian step on one of the buttons 150 after the first pedestrian initiated the signal action, the same operation takes place, and the second energization of coil 45 159 again pulls armature 167 to cause pawl 169 to move ratchet 125 a second notch in a clockwise direction. This swings switch arm 17 from switch point 126 to switch point 171, thereby cutting in a low resistance unit 171 into the circuit 50 of the motor A, thus causing the motor to slow down slightly to increase the cycle time, say five seconds, so as to permit the second pedestrian to cross the main highway without danger of the signals initiated by the first pedestrian turning on him when he is partly across the main highway.

Should a third pedestrian step on one of the buttons 150 following the second pedestrian, coil 55 159 is again energized to advance the arm 17 of the step-by-step switch from point 171 to point 173, thereby cutting in a second resistance unit 174 into the motor A circuit to slow down the rotation of the motor still more, say another five seconds.

65 Lastly, if a fourth pedestrian follows a third pedestrian, the switch arm 17 is moved from switch point 173 to switch point 175 to cut in the high resistance unit 176 into the circuit of the motor A so that the motor is slowed down to 70 a relatively low speed, say five more seconds slower, thus permitting at least four pedestrians to cross successively without danger of the traffic lights changing against them to start the main highway traffic into operation before they have 75 had an opportunity of crossing the main highway

in safety. Of course, many more pedestrians than four may cross, but four in succession is sufficient to start the selective traffic control by pedestrians, and successively increase the signalling time from say ten seconds to twenty-five seconds or more or less. Thus, the pedestrian traffic may not retard the main highway traffic for more than the predetermined time, so that the system is fool-proof, there being only sufficient interruption of the main highway traffic to permit the safe passage of pedestrians for a period of say 10 to 25 seconds, this time, of course, being variable by proportioning the resistance units 172, 174 and 176 in a predetermined ratio to procure the desired slowing up of the signal operation. This may be done by making the resistance units adjustable in accordance with common practice.

It will be recalled that when cam 80 closed contacts the completion of the cycle of signals 20 initiated by the cross traffic, coil 122 was energized to pull pawl 124 away from the ratchet 125, this connection also knocking pawl 169 away from the ratchet 125, which is thus released so 25 that spring 170 is free to rotate the switch until switch arm 17 again engages starting with point 18, and all of the resistance units are cut out of the motor circuit in readiness for the next starting operation. It will also be recalled 30 that at the time that coil 122 for resetting the step-by-step switch was energized, relay 157 was also energized, this action causing the armature 156 of the latter to break the circuit between the contacts 155, which also breaks the 35 circuit through the selector or step-by-step switch solenoid 159, so that any further closing of the pedestrian's buttons 150 would have no effect on the system. When this took place, locking pawl 177 engaged armature 156 to hold 40 it down after relay 157 was deenergized, so that the break in the circuit occasioned by energization thereof was maintained. When the entire signalling cycle was completed, cam 100 closed contacts 102 to energize coil 118, which disengage pawl 177 from armature 156 of relay 157. 45 to reset the same in readiness for the next operation.

In precisely the same way that successive pedestrians may increase the signal time, successive cross-traveling vehicles may increase the 50 length of the signal cycle by arranging the steel contacts 23 and 23' as the pedestrian's buttons 150 are arranged to operate the selector switch, or another one like it connected in parallel therewith, to cut resistances 172, 174 and 176 successively into the circuit of motor A, so that the signal cycle time is increased, say, five successive vehicles which engage either contact 23 or 23'. The idea and circuit arrangement is identical, so it is deemed sufficient to describe one 60 of them for a complete understanding of the other. This also applies to any other signal by cycle such as that initiated by a left-turning vehicle in the manner to be described later in 65 connection with Figs. 2 and 2a.

It will be seen that the automatic signalling system illustrated in Fig. 1 is controlled individually by the cross street traffic, or by the pedestrian traffic, and that it is only in operation when a vehicle approaching from the cross street or a pedestrian seeking to cross the main highway initiates the operation thereof, and that it is otherwise out of operation because it is desirable to maintain main highway traffic continuous when there is no cross traffic to inter- 75

rupt it. It is well known that when intersections such as the one described are not equipped with some kind of a signal system, or when the ordinary signal system of alternately cyclic operation of the main highway and cross street lights is employed, the main highway traffic is frequently needlessly stopped at periodic intervals when there is no cross traffic requiring such action.

10 Accordingly, the present invention provides for energization of the signal system only when there is cross traffic requiring the stoppage of the main highway traffic and at other times the main highway traffic flows continuously without interruption, and the signal lights are not illuminated at all. Thus, the apparatus of the present invention is only used when necessary, and facilitates traffic flow and eliminates the use of the expensive continuously operating traffic systems or the services of an attendant or traffic officer.

Now, referring to Figs. 2 and 2a, which are complementary drawings constituting one complete schematic circuit, this arrangement goes a step further than the traffic control system described in connection with Fig. 1 in that provision is not only made for controlling the signals by means of a cross street vehicle and pedestrians, but means are also provided to permit a vehicle seeking to make a left turn into the cross street from the main highway to appropriate to itself the signals if already initiated by a pedestrian or cross-traveling vehicle and, if this is not the case, to initiate such signals as will stop all traffic interfering with the left turn so as to permit it to make the turn by energizing the appropriate signal lights.

In general, the mechanism controlled by the pedestrians and the cross street traffic is the same as that described in connection with Fig. 1, but with certain supplementary additions which form elements of the additional mechanism mentioned above. For convenience, however, the circuits common to both Figs. 1 and 2-2a will be briefly traced, a cipher being added to the common reference characters of Fig. 1 in order to avoid confusion and yet enable the common elements of the two circuits to be compared most readily.

50 Assuming as before that a vehicle is approaching the intersection from the north on the cross street and that, after having observed the warning indicators 11 and 12 several hundred feet ahead of the intersection, he proceeds cautiously until he engages street contact 230 (or 230'). From battery 200 the circuit may be traced to the cross traffic vehicle contacts 230 (and 230') through closed switch 210, terminal 211, where the circuit divides, wire 220, terminal 212 where this branch of the circuit divides again, one branch following wire 213, terminal 214, wire 215, terminal 216, wire 217, terminal 218, wire 219, wires 1520, street contacts 230 and 230', wires 1530, terminal 1531, wire 246, solenoid 250, wire 260, terminal 261, and wire 262 back to battery 200.

Energization of solenoid 250 causes armature 250' to bridge contacts 270, thus completing another branch circuit from terminal 216, wire 280, 70 relay contacts 270, relay armature 250', wire 290, terminal 291 where the circuit divides, one branch including relay 330, which is accordingly energized, and wires 350, 260, and 261 back to battery 200. The other branch of the last named circuit 75 is traceable from terminal 291 through wire 300,

relay 320, and wires 321 and 262 back to battery 200. Energization of relay 320 pulls down armature 360 to bridge contacts 370, thus completing the branch circuit from terminal 212, relay contacts 370, armature 360, wire 371, terminal 372, 5 where the circuit divides, one branch going to selective switch segment 460, wire 470, relay contacts 471, normally closed by the armature 472 of relay 473, wire 474 to motor A, and return to wires 440, terminal 441, and wire 442, to battery 10 200. When relay 320 was energized, its armature 360 locked in closed position by the pawl 381, which is releasable by coil 1080 in the manner to be described later. Similarly, the armature 390 of relay 330 is dropped in closed position by pawl 15 410, which is releasable by coil 1140 in a manner to be described later.

As the motor A begins to rotate, cam 500 drops its follower 520 off its high point 530 to the no-motion surface that comprises the greater portion 20 thereof. This action causes spring contacts 540 to close, which initiates the signalling operation. At this time, contacts 610 of cam 600 are also closed, and contacts 770 of cam 670 are closed, while contacts 680 are open. Contacts 540 are 25 connected by wire 550 to energized wire 474, mentioned above. This completes a circuit from contacts 540 through wire 560, wire 570, wire 620, contacts 610 of cam 600, terminal 611 where the circuit divides, one branch following wire 630, 30 wire 650, contacts 770, wire 790, both amber main highway lights 780, and wires 710, 720, and 442 back to battery 200. Thus the warning signal is flashed on the main highway traffic which, in the absence of any cross traffic, is normally 35 flowing without interruption from any signal lights.

It will be recalled that the circuit just traced divided at terminal 611, and the other branch follows wire 612, back contacts 613, which are 40 normally closed by armature 614 of relay 615, wire 616, relay 617, which is accordingly energized, and wires 618 and 262 back to battery 200. Energization of relay 617 causes its armature 619 to bridge its contacts 621. The closure of relay 45 617 completes a circuit traceable from battery 200, terminal 211, wire 622, wire 623, armature 619, and contacts 621 of relay 617, where the circuit divides, one branch following wire 623 to south cross street red light 624, and wires 720 and 442 back to battery 200, the other branch of the circuit following wire 625 to north cross street red light 626 and wires 720 and 442 back to battery 200. Thus, in this condition, the signalling system for cross street traffic is stopped by red 55 lights 624 and 626, and the amber lights 780 are flashed on the main highway traffic.

The next action is caused by follower 580 riding up on the high point 590 of cam 600 to break the connection between contacts 610. This 60 breaks the circuit to the main highway amber lights 780, which has just been traced, and also deenergizes relay 617 so that its armature 618 is released and is drawn upwardly by coil spring 627 to break the connection between relay contact 621 and the circuit to cross street red lights 624 and 626. Accordingly, the main highway amber lights 780 and the cross street red lights 624 and 626 are extinguished.

Simultaneously with this action, the follower 70 of cam 900 drops into the notch thereof and closes contacts 860, thus closing a circuit from energized wire 474, wire 550, contacts 540 of cam 500, wires 570 and 850, contact 860 of cam 900, to terminal 861, where the circuit divides, one 75

branch following wire 1070, reset coil 1080 and wires 321 and 262 back to battery 200. The energization of reset coil 1080 disengages pawl 381 from armature 360 to release the same, which breaks the connection between relay contacts 370. This breaks the circuit to the motor through wire 470, but the motor circuit is maintained, however, through relay 330 by a circuit traced from battery 200, wires 220, terminal 212, wire 221, contacts 400 of relay 330, armature 390, selector switch segment 460, selector switch point 180, wire 190, contacts 191, which are bridged by armature 192 of normally closed relay 193, and wire 194 to motor A, so the motor keeps on rotating.

15 It will be recalled that the circuit previously traced divided at terminal 861, and the remaining branch may be traced from wire 870, relay 871 and wires 618 and 262 back to battery 200. Energization of relay 871 pulls down armature 872 against the tension of spring 873, to close the contacts 874 thereof. This completes two circuits, one traceable from battery 200, wire 622, wire 875, one of the contacts 874 of relay 871, wire 878, west main highway red light 877, and wires 710 and 720, and 442, back to battery 200. The other circuit closed by relay 871 may be traced from battery 200, wire 622, wire 875, armature 872, relay contact 874, wire 878, terminal 879, where the circuit divides, one branch following wire 881, east main highway red light 882, and wires 710, 720, and 742, back to battery 200. The red lights 877 and 882 accordingly stop main highway traffic.

35 Another branch of this circuit may be traced from aforesaid terminal 861, wires 883 and 884, contacts 840 of cam 800, whose follower is still riding on the no-motion high point thereof, wire 885, relay 886, and wires 618 and 262 back to battery 200. This energization of relay 886 pulls down its armature 887 against the tension of springs 888, to close contacts 889. This establishes a circuit from battery 200 through wires 622, and 891, coil spring 888, and armature 887, 40 where the circuit divides between the two contacts 889, one branch following wire 892, south cross street main light 893, and wires 720 and 442 back to battery 200. The other branch of this circuit may be traced from the other contact 889 of relay 886 through wire 894, north cross street main light 895 and wires 720 and 442 back to battery 200. Thus both cross street green lights 893 and 895 are energized at the same time, so that cross street traffic is permitted to 45 cross the main highway, while the main highway traffic is stopped.

Next, the follower 580 of cam 600 drops off its high point 590 and again closes contacts 610, and shortly thereafter the follower of cam 800 drops into the notch thereof, closes contacts 830 while breaking contacts 840. The separation of contacts 840 by the action of contacts 800 breaks the circuits through relay 886, so that coil spring 888 may withdraw armature 887 from contacts 889, thus breaking the circuit through both cross street green lights 893 and 895. Closure of contacts 830 by cam 800 establishes a circuit traceable from energized wire 474, wire 550, contacts 540 of cam 500, wires 560, 570, and 850, contacts 860 of cam 900, terminal 865 where the circuit divides, one branch following wires 883, 884, contacts 830 of cam 800, terminal 862 where the circuit again divides, one branch following wire 863, both cross street amber lights 864, wires 720 and 422 back to battery 200. Thus the cross

street amber lights are lighted when the cross street green lights are extinguished.

The second division of the circuit at terminal 862 follows wire 866, terminal 1572 where the circuit divides, coil 867, and wires 868, 260 and 5 262, back to battery 200, while the other branch energizes relay 1570 to pull down its armature 1560 to break the connection between normally closed contacts 1550, pawl 1770 locking relay 1560 down, while the circuit is completed 10 through wires 1571, 260 and 262 to battery 200. This opens the circuit to selector switch operating solenoid 1590 which is now inoperative. Energization of coil 867 causes pawl 1240 to rotate about its pivot away from ratchet 1250, and this 15 pawl also knocks pawl 1690 away from ratchet 1250, which permits the coil spring 1700 thereof to restore the contact arm 170 to initial switch point 180. This action has no particular significance at this time, but its function will be described later.

Now referring to closure of contacts 610 by cam 600, this action takes place an instant after the action of cam 800, and effects the illumination of cross red lights 626 and main amber lights 780. This circuit is traceable from wires 474 and 550, contacts 540, wires 560, 570, and 620, contacts 610 of cam 600, and terminal 611, where the circuit divides, one branch following wires 630 and 650, and contacts 770 of cam 670, wire 30 790, both main amber lights 780, and wires 710, 720 and 442 back to battery 200. The other branch of this circuit may be traced from terminal 611, wire 612, back contact 613 of relay 615, wire 616, relay 617 and wires 618 and 262 back 35 to battery 200. Energization of relay 617 pulls down its armature to close the aforementioned circuit to cross red lights 624 and 626, which are now illuminated, and cross traffic is stopped.

Next the follower of cam 900 rides upon its 40 no-motion surface and breaks contact 860 to de-energize relay 871 whose armature 872 is raised by spring 873 to break the connection between contact 874. This section of relay 871 breaks the circuit to main red lights 877 and 882 which 45 are now extinguished, while the main amber lights 780 are still illuminated. At the same time the reset coil 1080 of relay 320 is deenergized and the relay is restored for the next operation, and solenoid 1590 and reset coil 867 of the selector switch are also deenergized, so that pawls 1240 and 1690 are allowed to reengage the ratchet 1280. Simultaneously with these operations the cross street amber lights 864 are extinguished 55 and the cross street signal light cycle is completed, no more signal being shown until the system is again energized.

Slow acting cam 670 follows this operation and its follower 680 rides up on the no-motion surface thereof and closes contacts 680 and opens contact 770, this last action extinguishing main amber light 780 while the first action initiates a circuit traceable from energized wire 474, wire 550, contacts 540 of cam 500, wires 560, 570 and 620, contact 610 of cam 600, terminal 611, wires 630 and 650, contact 680 of cam 670, wire 690, relay 691, wires 618 and 262 to battery 200. Relay 691 pulls down its armature 692 against the tension of spring 693 to connect contacts 694. This establishes a circuit from battery 200, wires 622 and 695, armature 692 to relay contacts 694 where the circuit divides, one branch traversing wire 696 to terminal 697 where the circuit again divides, one branch to open contact 698 of relay 699 and the other via wire 701 to east main green 75

light 702 and wires 710, 720 and 422 back to battery 200. The other branch circuit may be traced from the other contact 694 of relay 691 via wire 703 to terminal 704 to terminal 734, 5 where the circuit against divides, one branch to open contact 705 of relay 706 and the other via wire 707, the west main green light 708, and wires 710, 720 and 442 back to battery 200. Thus the main highway traffic is restored by the 10 simultaneous energization of main green lights 702 and 708.

As the motor A continues to rotate the follower of reset cam 1000 drops into the notch thereof and closes contacts 1020, thus establishing 15 a circuit which may be traced from wire 474, wire 550, contact 540 of cam 500, wires 560, 570 and 1040, contact 1020 of cam 1000, wire 1001, terminal 1002 where the circuit divides, one through reset coil 1140, which disengages pawl 410 20 from armature 390 of relay 330 so that contacts 400 are again opened, the circuit being completed through wires 1003, 260 and 262 to battery 200. The other branch of this circuit may be traced from terminal 1002, reset coil 1004, and 25 wires 1008, 260 and 262 to battery 200. Energization of reset coil 1004 disengages pawl 1770 from armature 1560 which again bridges contact 1550 in readiness for the next operation. The signal system is now deenergized, and follower 30 520 rides upon the high point 530 of cam 500 to separate contacts 540, thus breaking the signal cycle initiating circuit and all signals are extinguished and main highway traffic continues to flow uninterrupted.

35

Left-turn signal control

It will be observed that the operation of the circuit illustrated with reference to Figs. 2 and 2a is so far similar to the apparatus illustrated 40 by Fig. 1, the difference being principally the individual operation of the main and cross red and green lights by the interruption of the double contact relays 699, 871, 617, 691, 886, 193 and 45 473, in the first named arrangement, and whose function procures no different results in ordinary traffic than the last named arrangement. These relays are, however, operative to procure a different combination of signals when a vehicle on the main highway desires to make a left turn into 50 the cross street. For this purpose vehicle-controlled contacts 2000 and 2000' are placed in the main highway adjacent the center thereof as shown in Fig. 3, the main highway still being considered for convenience as running east and 55 west and the cross street as running north and south, the latter having the vehicle controlled signal initiating contact 230 and 230' and the former having the pedestrian-controlled buttons 1500, whose operation and the control of the 60 signal cycle time being precisely the same as described in connection with Fig. 1, and further description is accordingly not necessary.

In operation of the left turn signal control, a vehicle about to enter the signal zone from the 65 west on the main highway, for example, and desiring to execute a left-turn to the north into the cross street, draws to the center of the main highway stops and closes contacts 2000. It will be observed that vehicles seeking a right turn pass 70 to the right of the main highway and avoid contacts 2000. The circuit controlling action of the latter is so arranged with a time lag, for example, as to be unresponsive to the momentary weight of passing cars and is responsive only to 75 the weight of a car standing thereon.

Now referring to the circuit diagram of Figs. 2 and 2a, closure of left turn contact 2000 initiates a circuit traceable from battery 200, wires 220, 213, 215, 217 and 219, left turn contact 2000, wire 2001, relay 2002, and wires 2003, 260 and 262 back to battery 200. Energization of relay 2002 pulls down its armature 2004 to bridge contacts 2005, the armature being locked in this position by pawl 2006. This completes a circuit traced from battery 200, wires 220, 213, 215, 217, 10 219, and 2007, relay contacts 2005, wire 2008, relay 2009, and wires 2010, 260 and 262 back to battery 200. Relay 2009 pulls down one end of armature 2011, which is pivoted at 2012. This action causes contacts 2013 and 2014 to bridge 15 contacts 2015 and 2016, respectively, and the depressed end of armature 2011 is locked down by pawl 2017.

Considering the effect of this bridging of contact 2015 by contacts 2013 first, the circuit is 20 traceable from battery 200, wires 220, 213, 215 and 217, terminal 218, wire 2018 to contactor where the circuit divides, one branch being traceable through wire 2019, relay 706 and wires 618 and 262 back to battery 200, while the other 25 branch is traceable from the other contact 2015 of relay 2009, wire 2020, relay 615 and wires 2021, 618 and 262 back to battery 200. Energization of relay 706 causes its armature 2022 to bridge contacts 705, thereby closing a circuit traceable 30 from battery 200, wire 622, relay armature 2022 where the circuit divides, one branch following wire 881, east main red light 882, wires 710, 720 and 442 back to battery, and the other branch is traceable from the other contact 705 of relay 35 706, wire 707, main west green light 708 and wires 710, 720 and 442 back to battery 200.

The aforementioned energization of relay 615 caused armature 614 to break the normal connection between contact 613 and connect contact 40 2023. This completes the circuit traceable from battery 200, wire 622, contacts 2023 of relay 615, relay 617 and wires 618 and 262 back to battery 200. Energization of relay 617 causes its armature 619 to bridge contacts 621, thus completing a 45 circuit traceable from battery 200, wires 622 and 623, spring 627 and armature 619 of relay 617 where the circuit divides, one branch following wire 623, south cross red light 624 and wires 720 and 442 back to battery 200, while the other 50 branch follows wire 625 from the other contact 621, a relay 617, north cross red light 626 and wires 720 and 442 back to battery 200. Thus the left turning vehicle entering the intersection along the main highway from the west engaged 55 left turn contacts 2000 and initiated the signal cycle just traced whereby it obtained its right of way into the north cross street, flashing the west main highway green light for the turn, the east main highway red light against west moving 60 traffic so that the turn might be completed and also stopped cross street traffic so that no cross moving vehicles would interfere with its progress during the left turn.

It is seen that this left turning vehicle immediately assumed control of the traffic mechanism 65 the moment it closed left turn road contacts 2000 and it was enabled to take precedence over other traffic, and this is desirable because left turning vehicles by stopping in the middle of the highways from which they seek to turn interrupt traffic which would otherwise be dispatched without interruption and with greater rapidity so it is 70 of advantage to get the left turning traffic out of the way as soon as possible. This appro- 75

priation of the signal control by the left-turning vehicle takes place whether or not the signals are in operation because of initiation by a cross-travelling vehicle or pedestrian.

5 It will be recalled that the left-turning vehicle by energizing relay 209 also caused connector 2014 to bridge contacts 2016. This closure of contacts 2016 by connector 2014 establishes a branch circuit which may be traced from battery 200, wires 220, 213, 217, 2018, contact 2016, wire 2041, motor B and wires 321 and 262 back to battery 200. The motor rotates at a speed sufficient to permit the left-turning vehicle to clear the other traffic and make the left turn. 10 This time interval is determined by cam 2032, and as soon as the follower 2042 drops into the notch 2043 thereof, contacts 2031 are closed and the left-turning signal control mechanism is reset. This resetting action may be followed by 15 tracing the other branch circuit for contact 2016 of relay 2009 from battery 200, wires 220, 213, 215, and 217, terminal 218, wire 2018, connector 2014, wire 2025, relay 2026 and wires 321 and 262 and back to battery 200. Energization of relay 2026 causes its armature 2027 to bridge contacts 2028, thus initiating a circuit traceable from battery 200, wires 220, 213, 2029, which is not completed until normally open contacts 2031 are closed at the end of the cycle by cam 2032 which 20 is driven by motor B set in operation in the manner described.

When follower 2042 of cam 2032 drops into the notch 2043 thereof, contacts 2031 are closed and the circuit is completed via wire 2033, contacts 35 2028 of relay 2026, wire 2034, terminal 2035 where the circuit divides, one branch energizing reset coil 2063 and being completed through wires 2003, 260 and 262 back to battery 200, while the other branch from terminal 2035 follows wire 2036 to reset coil 2037, wires 2038, 260 and 262 back to battery. Energization of reset coil 2063 pulls pawl 2006 away from armature 2004 of relay 2002 and the connection between contacts 2005 is broken, thus restoring the relay 40 2002 which was energized by the closure of the left turn main highway contacts 2000. The breaking of the connection between contacts 2005 of relay 2002 de-energizes relay 2009 and the energization of reset coil 2037 of this last named 45 relay pulls pawl 2017 away from armature 2011 which is now released to break the connection between connector 2013 and contacts 2015 and between connector 2014 and contacts 2016 of said relay 2009. The coil springs 2039 restore armature 2011 to its normal position shown in Fig. 2. 50 Also during the time that the left turn signals are energized, which is determined by cam 2032 since this cam resets the left turn signal mechanism, the initial connection of contacts 2016 of relay 2009 by connector 2014 energized relays 473 and 193, causing their respective armatures 472 and 192 to break connection between respective contacts 471 and 191.

It will be recalled that armature 192 normally completes one of the circuits to master motor A and that this circuit is therefore broken while the left turn signal mechanism is in operation, and that armature 472 of relay 473 normally completes the other remaining circuit to the master 55 motor A so that this circuit is also broken. Accordingly, while the left turn signal mechanism is in operation, the master signal motor A is stationary and all normal signals remain in the particular energized condition which they were in when the left-turning vehicle closed main high-

way contacts 2000. Thus the left turning vehicle appropriates to itself the signals which are necessary to permit it to negotiate the desired left turn and in so doing it also stops traffic moving against it from all directions so that it may negotiate 6 the turn safely and furthermore it stops the normal signals where they are and the normal signal system does not again come into operation until left turn cam 2032 drops its follower 2042 into its notch 2043 to close contacts 2031 which resets 10 the left turn mechanism by releasing armature 2004 and restores the normal signal system by de-energizing relays 473 and 193 so as to permit their respective armatures 472 and 192 to re-close 15 the alternative circuits to the master motor A which controls the normal signal cams. Of course, if the normal signals are not in operation at the time that the left-turning vehicle engages street contacts 2000, the breaking of the circuit to motor A has no effect since the motor is not 20 then in operation.

Precisely the same signal appropriation takes place when the vehicle approaching from the east along the main highway moves to the center of the main highway and closes contacts 2000' 25 in the first movement toward making a left turn to the south into the cross street. A different set of initiating elements are provided but these elements are connected in parallel with those controlled by left turn contacts 2000 and so the 30 cycle is exactly the same. For example, closing of contacts 2000' initiates a circuit traceable from battery 200, wires 220, 213, 215 and 217, terminal 218, wire 219, left turn contacts 2000', 35 wire 2045, relay 2046 and wires 2003, 260 and 262 back to battery 200. Relay 2046 corresponds to relay 2002 whose operation was described in detail above. It will be seen that energization of relay 2046 effects completion of a circuit traced from battery 200, wires 220, 213, 215, 217, 219 and 40 2007, contacts of relay 2046, relay 2047 and wire 260 back to battery 200. Relay 2047 swings armature 2011 around its pivot 2012 to bridge the sets of contacts 2048 and 2049. Bridging of contacts 2049 completes a circuit traceable from battery 200, to terminal 218, wire 2018 to contacts 2049, where the circuit divides, one branch being traceable through wire 2119, relay 699 back to battery 200, and the other branch following wire 2226 to relay 615 and back to battery 200. Energization of relay 699 bridges contacts 698, thereby closing a circuit from battery 200 to relay contacts 698, where the circuit divides, one branch following wire 701, east main 55 green light 702 and wire 720 back to battery 200, and the other branch follows wire 876, west main red light 877 and wire 720 back to battery 200.

The aforementioned energization of relay 615 causes armature 614 to break the connection between contacts 613 and bridge contacts 2023. As before, this causes energization of relay 617, which bridges contacts 621. The circuit completed by relay 617 divides, and one branch follows wire 623 to south cross red light 624 and 65 back to battery, while the other branch follows wire 625 to north cross red light 626 and back to battery.

It will be seen that east main green light 702 is lighted to start the vehicle on its left turn, west 70 main red light 877 is lighted to stop west-travelling traffic, so that the left-turning vehicle may move south into the cross street, and both cross street red lights 624 and 626 are energized to stop cross traffic and permit the left-turning vehicle 75

to complete its turn. The signal cycle is restored as before.

It is to be understood that each cross-travelling vehicle, pedestrian, or left-turning vehicle which initiates or otherwise controls a signal cycle is considered as a single traffic unit. Thus, a pedestrian seeking to cross the main highway, is like a cross-travelling vehicle, a unit of traffic, and if more than one vehicle or pedestrian should engage a corresponding street or side-walk treadle or contact at the same time, or treadles or contacts which are connected in parallel, the aggregate of this signal initiating or controlling are considered as a single traffic unit. All following vehicles or pedestrians which reenergize the system after one cycle or reenergize the selector switch to increase the time of the signal cycle, whether one or more vehicles or pedestrians at the same time or within a predetermined time limit so that their joint actions procure a single effect, are all considered successive units of traffic.

It is desirable to facilitate right turns to or from the main highway inasmuch as no crossing of traffic is necessary when a right turn is executed, and so the initiation or operation of the signal equipment is not necessary. As mentioned above in connection with the left turn, vehicles seeking to execute a right turn draw toward the curb and so avoid the left turn 2000 or 2000' contact in the main highway, which is spaced from the curb, so that it is not actuated to initiate or appropriate the signals. Where the width of the cross street is sufficient to permit it, the cross street contacts 230 and 230' are also preferably spaced from the curb to allow the right-turning traffic to avoid it. In this arrangement the cross street contacts 230 and 230' resemble the left turn contacts 2000 and 2000' in position in the street. Of course, the cross street may be equipped with left turn control and if this is done, the right-turning traffic will automatically avoid the contact, which is spaced from the curb.

In the arrangement illustrated in Figs. 3 and 4, a left-turning vehicle coming from the north actuates contact 230, so that both main red lights, and both cross green lights are lighted in the manner described, thus permitting another left-turning vehicle coming from the south to execute a left turn at the same time. Of course, either the main highway or the cross street or both may be equipped with both the straightway contacts 2000 or 2000' and the left turn contacts 230 and 230', but as this complicates the situation considerably, it would probably not find much use except under exceptional circumstances.

The term "left turn" as employed herein, refers primarily to the manner of turning from one traffic lane across another traffic lane on the same street, as where an operator of a vehicle in traffic moving at the right-hand side of the street makes a left turn across the left-hand side of the street. However, in localities where it is the custom for vehicles to travel along the left-hand side of the street, as is the case in many foreign countries, the same kind of turn would be a "right turn," and it is to be understood that for the purposes of this invention, the term "left turn" used herein is synonymous with the term "right turn" in cases where traffic customarily travels on the left-hand side of the street.

The new invention provides many apparent advantages over the continuous cycle type of traffic control systems, in which a commutator or the like uniformly controlled the signals in oppo-

site directions, or a special attendant or traffic officer was employed to throw a switch from time to time to regulate the traffic in accordance with its density. In considering these advantages, it should be emphasized that the system of this invention is normally dormant or inactive so that the main traffic in one direction or right turns at the intersection are not interfered with but allowed to flow freely with despatch. It is only when a vehicle, pedestrian, or other traffic unit seeks to make a left turn from or to enter the traffic stream from outside such as from a side or cross street, other than by a right turn, that the signal equipment is energized and the operation of the signal cycle initiated.

It is to be understood however that the term "intersection" does not necessarily mean the intersection, crossing or emergence of straight streets, roads or thoroughfares, but broadly means the joining of two or more traffic lanes whether or not any of these lanes is straight. For example, a traffic carrying lane may curve such as around a corner, while the intersecting lane may enter at the corner in the shape of a T. In this case either the angle lane or the intersecting lane may be the "main highway." Also, "main highway" does not necessarily mean a boulevard, main street, or the like, but a traffic lane which carries either more or heavier traffic or traffic whose dispatch is considered more important or desirable for any reason, while "cross street" or "side street" means any traffic lane entering the traffic lane defined as the main highway, whether or not the traffic traversing either is vehicular, pedestrian, railway, or the like. However, for convenience and clarity, a traffic lane which passes entirely through an intersection, whether on the straight-away, curve or angle, and which is formed by two aligned streets across the intersection, is called a "main highway" or simply "highway," while a traffic lane which approaches and terminates on the intersection is called a "street" or "cross-street." By the present invention a complete system may be installed conveniently at any intersection such as in outlying districts or along arterial highways where the highway traffic density greatly exceeds that entering the highway from the cross or side streets or crossing the same from the cross streets. Such intersections greatly outnumber those in which traffic is substantially uniform in cross directions; i. e., along the main highway and crossing or entering the main highway from cross or side streets. Accordingly, the control of the system by the relatively few vehicles entering or crossing the main highway from the cross or side streets, or by pedestrians seeking to cross the main highway, or by vehicles seeking to make a left turn from the main highway into the side street, is greatly to be desired, and the system of this invention is adapted to provide these requirements.

Also by providing preindicating signals or arbitrary warning indicators along the roadside several hundred feet ahead of the intersection for defining the signal zone, vehicles are warned that they are approaching a zone of automatic signal control and should proceed with due care, these arbitrary indicators being so designed as to mean just this to the operator of a vehicle.

Furthermore, the system of this invention is entirely self-contained, and is provided with its own local source of power for its operation so that it may be installed anywhere without regard to outside power facilities. Inasmuch as the sys-

tem only operates when cross traffic or left-turning traffic initiates such operation, the mechanism is only in use a part of the whole day and is dormant for long intervals, especially at night, 5 whereby depreciation because of excessive use and the expense caused by unnecessary power consumption is eliminated.

While a preferred embodiment of the invention has been illustrated and described herein, it is 10 to be understood that the invention is not limited thereby but is susceptible of many changes in form and detail within its scope, and any one, any two, or all of the several separately operated and coordinated signal controlling arrangements 15 may be used at will so that the system of this invention may be adapted to suit all requirements of automatic traffic control.

I claim:

1. A traffic control system for two substantially 20 parallel and opposite traffic lanes, comprising a "stop" signal for each lane, means so disposed as to be actuated only by a unit of traffic in one lane taking a position to make a turn across the other lane and not by through traffic in said one 25 lane, and means to be actuated by said traffic actuatable means when said traffic actuatable means is actuated to provide a stop signal for said other lane.

2. A traffic control system for the intersection 30 of a cross-street with a highway, comprising an electrical traffic signal, a source of power therefor, switch means in the circuit of said signal and said source for controlling the energization of said signal, timing mechanism for operating 35 said switch means, an electric motor whose speed is responsive to the resistance of its circuit for driving said mechanism, an energizing circuit for said motor, devices at said cross-street adjacent

the intersection operable by a traffic unit seeking to enter the highway and operatively connected to said motor for controlling the same, an electrical resistance in the circuit of said motor, and means actuated by a second operation of said devices for varying said resistance, whereby the motor speed is varied to vary the length of time of the signal cycle initiated by the first traffic unit. 5

3. A traffic control system for intersecting 10 traffic highways, one of said highways comprising a plurality of traffic lanes for traffic moving in one direction, a Go signal for one lane of said plurality of lanes, a Stop signal for the other of said intersecting highways, and traffic actuatable means in said Go signal controllable lane 15 actuatable by a unit of traffic in said one lane taking a position to make a turn across an interfering traffic lane in other of said intersecting highways to actuate said stop signal. 20

4. A traffic control system for intersecting 25 traffic highways, one of the highways having a plurality of traffic lanes for traffic moving in one direction and at least one traffic lane for traffic moving in substantially a parallel and opposite direction, comprising a "stop" signal for each of the lanes and a "go" signal for one of the plurality of lanes moving in one direction, means so disposed as to be actuated only by a unit of traffic in a preselected lane of the plurality of lanes moving in one direction taking 30 a position to make a turn across the lane moving in the opposite direction and not by through traffic in the preselected lane, and means to be actuated by the traffic actuatable means wherein 35 said means is actuated to provide a "stop" signal for the other lanes of traffic.

PAUL P. HORNI.
